ROOFING DEVICE

Erich Gach, Chicago, Ill., assignor to Bird & Son, Inc., East Walpole, Mass., a corporation of Massachusetts

Application December 11, 1934, Serial No. 756,970

6 Claims. (Cl. 91—67.4)

This invention relates to a roofing device and has to do principally with the provision of a device and method for blind nailed roofings.

Heretofore blind nailed roofings and the like, 5 which depend on a viscous asphaltic cement to hold the laps or tabs to the underlying overlapped portions of the roofings, have had the cement applied by means of trowels, putty knives or the like with resultant slow and troublesome 10 application, and objectionable variations in the thickness and width of the cement thus applied. With such tools it is not possible to either pick up and hold any considerable amount of cement or apply it uniformly. Moreover, because of such 15 lack of uniformity, in order to secure a watertight lap it has been necessary to use an excess of cement with resultant waste and non-uniformity of surface.

The present invention concerns a device where- 20 by a considerable quantity of viscous roofing cement may be withdrawn from a can or container of the same and then be drawn along over the edge of the roofing adjacent the edge thereof or wherever it is desired to distribute a stripe 25 of cement of uniform width and thickness without spilling or any other application of the cement to other than the desired stripe. Other and additional advantages will hereinafter appear.

30 In the drawing which shows the preferred form of device and use thereof:

Fig. 1 is a perspective view showing the device in use;

Fig. 2 is an end elevation of the device with 35 the handle broken away;

Fig. 3 is a side elevation of the device of Fig. 2; and

Fig. 4 is a bottom plan view of the same.

Referring to the drawing in which like nu- 40 mers represent like parts, and particularly to Fig. 1,—there is there shown the application of strip rolled roofing to a roof structure 2, the strip of a lower course, partly broken away, being indicated at 4 and a strip of an overlying 45 course, also partly broken away, being shown at 6. Along the upper edge of the lower course 4 are driven roofing nails 8 which are placed suffi- 50 ciently close to the edge as to be covered by the lower overlapping edge of the course 6, so that the lower cut edge of the course 6 overlies and becomes substantially coincident with the lower edge of a stripe of cement 10 which is being laid thereon by the roofing device generally designated 12. This device 12 embodies a handle 14 55 having at one end an enlarged grip portion 16,

and at the other end firmly affixed thereto a cup-like portion having converging side and front walls 18, 20 respectively, and being open at the top as well as the bottom thereof as clearly shown in the figures. The side walls or wings 18 at 5 their lower edges are slightly curved in order to minimize the chance of the advancing pointed ends catching upon the roofing material, and the lower edges of the side walls 18 which confine the cement at the sides and preferably extend 10 somewhat below the lower or cement-spreading edge 22 of the wall 20 so as to leave said straight edge 22 sufficiently spaced vertically from the roofing as to lay upon the latter the cement in a stripe of the desired thickness. The thickness 15 can be regulated or varied by slightly raising or lowering the edge 22 as it is pulled along over the roofing, rolling the same on the lower edges of the side walls 18 as desired. In fact, the side walls need not extend below the edge 22 in which 20 case, however, the tool must be so held and moved as to keep the edge 22 vertically spaced from the surface of the roofing. The converging shape of the device is a valuable feature in that the same may be readily filled by forcing it 25 in and up against the wall of a cement container, even a relatively small container as shown at 24, which may be as small as a pint size. In this way the device may be readily and quickly filled 30 and the outside kept clear of cement because 30 the outside of the converging walls 18 and 20 does not contact the mass of cement in the container. Further, because of the converging character of the device, the cement does not tend 35 to stick to the same and, in use, the device readily clears itself and deposits substantially its entire content upon the roof in stripe form. There is thus provided a device which enables one to readily pick up a substantial quantity of cement and deposit the same in a stripe of uni- 40 form thickness along the desired area of the roofing, usually the edge, so that the cement is uniformly and precisely laid thereon. The blind nailing is therefore uniformly and completely 45 covered by a stripe of uniform width, the straight- 50 ly defined lower edge of which stripe forms a sufficiently straight and accurate line as to provide a mark or gauge to which the lower edge of an overlapping course may be laid. In this way parallelism between courses is insured for the 55 stripe is laid parallel to the upper edge of an underlying course.

Though the invention has been described primarily with respect to blind nailing and overlapping of courses, it will be appreciated that the 55

device is also applicable to the laying of serrated edge roll roofing, tabs and laps of strip shingles, side-lapped shingles, flashings and the like.

Having described my invention what I claim

5 is:—

1. A roofing device for applying viscous cement in a stripe to roofing, said device embodying a handle and a portion having cement-retaining side walls and a rear wall together defining a 10 substantially bottomless cup-like portion secured to said handle, said rear wall having a cement-spreading after edge between the bottom edges of the other walls of the device.

2. A roofing device for applying viscous cement 15 in a stripe to roofing, said device embodying a handle and a portion having converging cement-retaining side walls and a rear wall together defining a substantially bottomless cup-like portion secured to said handle, said rear wall having a cement-spreading after edge connecting the 20 parallel bottom edges of the other walls of the device.

3. A roofing device for applying viscous cement 25 in a stripe to roofing, said device embodying a handle and a substantially bottomless cup-like portion affixed thereto, said portion having cement-retaining side walls and back wall, said back wall having a cement-spreading after edge

offset above the bottom edges of the side walls of the device.

4. A roofing device for applying viscous cement 5 in a stripe to roofing, said device embodying a handle and a portion having converging cement-retaining side walls and a rear wall together defining a substantially bottomless cup-like portion secured to said handle, said rear wall having a straight after edge offset above the other bottom edges of the other walls of the device.

10 5. A roofing device for applying viscous cement in a stripe to roofing, said device embodying a handle and a substantially bottomless cup-like portion affixed thereto, said portion having converging cement-retaining walls two of which present parallel bottom edges and a straight after edge offset above and connecting said parallel bottom edges.

15 6. A roofing device for applying viscous cement in a stripe to roofing, said device embodying a 20 handle and a substantially bottomless cup-like portion affixed thereto, said portion having converging cement-retaining side walls and back wall, said back wall having a straight after edge offset above the bottom edges of the side walls of 25 the device.

ERICH GACH.
